DESIGN FOR A COMBINED BEVERAGE CONTAINER AND SERVING TRAY

Harry Lehman, Brooklyn, N. Y.

Application December 3, 1935, Serial No. 59,884

Term of patent 7 years

To all whom it may concern:

Be it known that I, Harry Lehman, a citizen of the United States, residing in the Borough of Brooklyn, county of Kings, State of New York, have invented a new, original, and ornamental Design for a Combined Beverage Container and Serving Tray, of which the following is a specification, reference being had to the accompanying drawing forming part thereof, wherein—

Figure 1 is a fragmentary top plan view of the combined beverage container and serving tray showing my new design; and

I claim:

The ornamental design for a combined beverage container and serving tray as shown.

HARRY LEHMAN.
